(57) **CLAIM**

The ornamental design for a carafe, as shown and described.

DESCRIPTION

FIG. 1 is a perspective view of a carafe on a base unit showing my new design in accordance with a first embodiment;

FIG. 2 is a side elevational view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a perspective view of an alternative embodiment of the carafe of the present invention with the base unit shown in broken lines.

The broken lines in the figures are for illustrative purposes only and form no part of the claimed design.
